PORTABLE PHONOGRAPH

Roger Scholle, New York, N. Y.

Application January 29, 1949, Serial No. 579

Term of patent 3½ years

(Cl. D56—4)

To all whom it may concern:

Be it known that I, Roger Scholle, a citizen of the United States, residing at New York, in the county of New York and State of New York, have invented a new, original, and ornamental Design for a Portable Phonograph, of which the following is a specification, reference being had to the accompanying drawing, forming part thereof, in which:

Fig. 1 is a top plan view of a portable phonograph, showing my new design;

Fig. 2 is a side elevational view;

Fig. 3 is an elevation as viewed from the left of Fig. 1; and

Fig. 4 is an elevation as viewed from the right of Fig. 1.

I claim:

The ornamental design for a portable phonograph, substantially as shown.

ROGER SCHOLLE.
